PUMP ACTUATING MECHANISM

Edgar W. Patterson, Long Beach, Calif., assignor,
by direct and mesne assignments, of one-half
to Charles M. O'Leary, Jr., and one-half to
C. M. O'Leary, both of Los Angeles, Calif.

Application February 20, 1933, Serial No. 657,530

11 Claims. (Cl. 74—41)

This invention relates to a pump actuating mechanism, and relates more particularly to a mechanism for actuating a well pump. It is a general object of the invention to provide a practical and effective well pump actuating mechanism that is of simplified and improved construction.

Another object of the invention is to provide a well pump actuating mechanism that may be embodied in a walking beam unit suitable for use in various situations, of that may be readily applied to an already installed walking beam unit.

Another object of the invention is to provide a mechanism of the character mentioned for actuating the reciprocating type of well pump in which all of the parts are directly connected or associated with the walking beam and its "Samson" post or supporting member.

It is another object of the invention to provide a pump actuating mechanism of the character mentioned in which the heaviest or one of the heaviest units or parts of the mechanism is carried by the walking beam and forms a counter balance for the string of pump rods operated by the walking beam.

It is another object of the invention to provide a pump actuating mechanism of the character mentioned in which the length or stroke of movement of the walking beam may be readily changed or varied.

Another object of the invention is to provide a pump jack or pump actuating mechanism of the character mentioned in which the power unit is carried by the "Samson" post in a simple and practical manner.

Another object of the invention is to provide a pump actuating mechanism of the character mentioned, including a novel and effective brake means operable to stop the walking beam in any position.

A further object of the invention is to provide a pump actuating mechanism that is efficient in operation and particularly simple and inexpensive of manufacture.

The various objects and features of the invention will be better and fully understood from the following detailed description of a typical form and application of the invention throughout which description reference is had to the accompanying drawings, in which:

Fig. 1 is a side elevation of the mechanism provided by the invention. Fig. 2 is an enlarged fragmentary vertical detailed sectional view taken substantially as indicated by line 2—2 on Fig. 1.

Fig. 3 is an enlarged front elevation view of the

arc on the forward end of the walking beam, being a view taken as indicated by line 3—3 on Fig. 1. Fig. 4 is an enlarged fragmentary side elevation taken substantially as indicated by line 4—4 on Fig. 2. Fig. 5 is an enlarged side elevation of a portion of the device. Fig. 6 is an enlarged fragmentary detailed sectional view taken as indicated by line 6—6 on Fig. 4. Fig. 7 is a fragmentary end elevation taken as indicated by line 7—7 on Fig. 5. Fig. 8 is an enlarged fragmentary sectional view taken as indicated by line 8—8 on Fig. 1, and Fig. 9 is a vertical sectional view taken as indicated by line 9—9 on Fig. 8.

The pump jack or pump actuating mechanism provided by the present invention may be varied considerably to adapt it for use in various situations, or for use in connection with different classes of equipment. The invention contemplates the provision of a complete pump actuating unit including a walking beam for reciprocating the pump rod and the "Samson" post supporting the walking beam, and contemplates the application of various parts of the mechanism to a previously constructed or installed walking beam unit. Throughout the following detailed disclosure, I will describe a typical form of the invention in which the walking beam unit may be considered as an element or part of the mechanism as initially constructed. It is to be understood that the invention is not to be taken as limited or restricted to the specific form or details about to be described, but is to be taken as including any features or modifications that may fall within the scope of the claims.

The form of the invention illustrated in the drawings, includes, generally, the "Samson" post 10, a walking beam 11 pivotally mounted on the upper end of the post 10, a power means 12 adjustably mounted on the "Samson" post 10, and an operating drive or connection 13 between the power means 12 and the walking beam 11.

In accordance with the broader aspects of the invention, the "Samson" post 10 may be constructed and mounted as desired or found practical. In the embodiment of the invention illustrated in the drawings, the unit includes a frame or base 14 carrying the "Samson" post 10. The base 14 may include spaced beams 15 adapted to be arranged on a floor F or other suitable support. The "Samson" post 10 may be in the form of a length of steel I beam as illustrated in the drawings. The lower end of the "Samson" post 10 is attached to the beams 15 of the base, and projects vertically upward from the base. Braces 16 may extend upwardly from the opposite

ends of the base 14 to the upper end portion of the "Samson" post 10 to brace and lend rigidity to the structure.

The walking beam 11 is mounted on the upper end of the "Samson" post 10 to pivot or oscillate about a horizontal axis. The walking beam 11 is provided to reciprocate the pump rod R in a manner to be subsequently described. The walking beam 11 may be formed of a length of steel I beam arranged to have its end flanges 17 form the upper and lower sides of the walking beam. The pump actuating unit or mechanism is positioned at the well so that the walking beam 11 has its inner arm 18 projecting over the head or upper end of the well as clearly illustrated in Fig. 1 of the drawings. The outer arm 19 of the walking beam may be somewhat longer than the inner arm 18. Suitable means is provided for pivotally attaching the lower flange 17 of the walking beam to the upper end of the "Samson" post 10 so that the walking beam may oscillate about a horizontal axis. The pivotal mounting illustrated in the drawings includes a bearing member 20 on the upper end of the "Samson" post 10 and a saddle 21 on the lower flange 17 of the walking beam. The bearing member 20 has a block or tongue 22 projecting downwardly between the spaced side flanges 23 of the "Samson" post 10 and attached to the said flanges by bolts 24. The bearing member 20 is yoked, having spaced upwardly projecting side parts 25. The saddle 21 is suitably attached to the lower flange 17 of the walking beam and has a block or tongue 26 projecting downwardly between the side parts 25 of the bearing member 20. A shaft or pin 27 extends through aligned horizontal openings in the side parts 25 and the tongue 26 to pivotally connect the walking beam 11 to the "Samson" post 10. The pivot pin 27 is tubular, having a longitudinal opening 28 extending through it from one end to the other.

The connection between the walking beam 11 and the string of pump rods R includes a head or arc member 30 on the outer end of the inner arm 18 of the walking beam. The arc member 30 has a convex outer face curved about the pivotal axis of the walking beam 11. A cable 32 or other flexible member extends through a flanged projection 33 at the upper end of the curved face 31 and has two spaced parts extending downwardly from the projection. The cable 32 engages the curved outer face 31 of the arm member and its lower ends are connected to the upper end of the pump rod R by a suitable clamp or connecting device 34. Spaced parallel ribs or flanges 35 project from the curved face 31 of the arc member to form channels for guiding the cable 32. The flexible cable 32 operating on the curved face 31 provides for the vertical reciprocation of the rod R without bending or flexing its upper portion.

It is a feature of the invention that the arc member 30 is attached to the walking beam so that it may be easily and quickly swung out of vertical alignment with the upper end of the well to allow tools, etc., to be freely passed into and out of the well. A central vertical web 81 is provided on the rear side of the arc member 30 and has a recess or notch 82 receiving the end portion of the walking beam arm 18. Flanges 83 are provided along the upper and lower edges of the notch 82 to cooperate with the flanges 17 of the walking beam. Two sets or pairs 84 and 85 of bolts extend through openings in the flanges 17 and 82 to removably attach the arc member 30 to the walking beam 11. The bolts 84 and 85 are

disposed at opposite sides of the web 81. When it is desired to swing the arc member 30 out of vertical alignment with the upper end of the well, the two outer bolts 84 and one of the inner bolts 85 are removed, leaving a single inner bolt 85. The arc member 30 is then free to pivot or hinge on the remaining bolt 85 and may be easily swung to a position at 90° to the longitudinal axis of the walking beam 11. When attached to the arm 18 of the walking beam by the single bolt 85, the arc member 30 is substantially statically balanced so that it may be very easily swung to any desired position. It will be apparent how the arc member 30 may be easily and quickly swung from its normal operative position to a position out of vertical alignment with the upper end of the well so that rods, tools, etc., may be freely passed into and out of the well.

The power means 12 is provided to operate or oscillate the walking beam 11 through the transmission or operating drive 13. In accordance with the invention, the power means 12 is carried by the "Samson" post 10. The power means 12 includes a suitable electric motor 36. Spaced beams or carriers 37 are attached to the vertical side flanges 23 of the "Samson" post 10 for vertical adjustment thereon, and project horizontally from the post to form a shelf or mounting for the motor 36. The shaft 38 of the motor 36 is preferably horizontal and in the same vertical plane as the pivot pin 27. A suitable brace or braces 39 may be attached to the under side of the beams 37 and may have its lower end attached to the "Samson" post 10.

The invention may include a stop means or brake means in connection with the power means 12 that is operable to stop and hold the walking beam 11 at any desired position. The brake means include blocks or shoes 40 for engaging or braking with a combination fly-wheel and drum 41 on the motor shaft 38. The brake shoes 40 are carried by lever members 42 pivoted adjacent their lower ends as at 43. An operating handle or lever 44 engages the outer side of one member 42 and is connected with the other member 42 by a rod 45. A spring 46 surrounds the rod 45 and is arranged under compression between the two members 42 to normally yieldingly hold the brake shoes 40 out of engagement with the drum 41. Upon the lever 44 being operated or pulled outwardly at its lower end, the lever members 42 are operated toward one another to bring the brake shoes 40 into engagement with the drum 41. A releasable ratchet 47 is provided in connection with the handle 44 to releasably lock the brake shoes 40 in tight braking engagement with the drum 41. It will be apparent how the stop means or brake means just described may be employed to stop and hold the walking beam 11 in any desired position immediately after the motor 36 has been stopped or to stop the walking beam in an emergency before stopping the motor.

The drive or operative connection 13 between the power means 12 and the walking beam 11 operatively connects the walking beam 11 with the motor 36 so that the motor 36 oscillates the walking beam 11 and thus reciprocates the pump rod R. The means 13 includes a pinion 50 on the inner end of the motor shaft 38. A shaft 51 is rotatable in the opening 28 of the pin 27 and projects from the opposite ends of the pin. A comparatively large gear 52 is provided on a projecting end of the shaft 51 and

meshes with the pinion 50 on the motor shaft. In accordance with the invention, one or more sprockets 53 of comparatively large diameter are provided on the outer arm 19 of the walking beam 11. In the particular case illustrated in the drawings, there are two sprockets 53, one at each side of the walking beam 11. A transverse shaft 54 supported by suitable bearings 55 carries the two sprockets 53. In the preferred 10 construction, the sprockets 53 are provided on the outer arm 19 of the walking beam at a point spaced a substantial distance from the pivotal axis of the beam. Comparatively small sprockets 56 are provided on the end portions of the shaft 15 51, and chains 57 pass over each pair of sprockets 53 and 56. The pinion 50 and gear 52 and the sprockets 56 and 53 are related to provide for a considerable reduction in speed between the motor shaft 38 and the large sprockets 53.

20 The invention includes means whereby rotation of the sprockets 53 causes oscillation or operation of the walking beam 11.

Crank links or connecting rods 60 are pivotally connected to the sprockets 53 and a suitable 25 relatively fixed object. The rods 60 are connected to the sprockets 53 at points offset from the axes of the sprockets. In the embodiment of the invention illustrated in the drawings, the lower ends of the rods 60 are pivotally connected 30 to the base 14. L heads 61 are provided on the lower end portions of the rods 60 and are adapted to pivot on a pin 62 carried in a bearing 63 on the base beam 15. In the preferred construction, pivotal connections are provided between the rods 60 and the L heads 61. The 35 lower ends of the rods 60 are yoked as illustrated in Fig. 9, and pivot pins 90 pass through openings in the upper arms of the L heads 61 and the yoked ends of the rods 60 to pivotally connect the rods and heads. Yoked heads 64 are provided on the upper ends of the rods 60 to receive the tongues 65 of connecting members or hub members 66. Pivot pins 67 extend through openings in the yoked heads 64 and 40 tongues 65 to pivotally connect the rod with the members 66. The members 66 carry pins 68 adapted to extend through openings 69 in the 45 sprockets 53.

In accordance with the invention, there is a 50 plurality of openings 69 provided in each sprocket for receiving a pin 68. The several openings 69 in each sprocket 53 are spaced different distances from the axis of rotation of the sprocket. By arranging the pins 68 in the different openings 69, the walking beam 11 may be given strokes of different lengths. It will be apparent how the pivoted rods 60 in connecting the rotating sprockets 53 with the stationary base 14, causes 55 oscillation of the walking beam 11 during the rotation of the sprockets 53. The pivotal connections on the opposite ends of the rods 60 are such that the rods will not bind or interfere with the free operation of the mechanism in the event that the walking beam 11 and/or 60 sprockets 53 carried by the beam are slightly out of alignment with the base 14.

The sprockets 53 on the outer arm 19 of the walking beam 11 operate to counter-balance the weight of the string of pump rods R and the 65 operated parts of the well pump. The invention includes a counter balancing means in addition to the sprockets 53. A plurality of removable weights 70 is provided on the outer end portion of the arm 19 of the walking beam 11. The 70 weights 70 are separately or individually remov-

able from the walking beam 11 so that the string of pump rods R may be properly or accurately counter-balanced. In the preferred form of the invention, the counter-balancing weights 70 are sectional, each being formed of two parts or sections connected by flange and bolt connections 71. The several weights 70 are arranged in a group on the walking beam arm 19 at a point outward of the pair of sprockets 53. Outwardly facing abutments or stops 72 are provided on the walking beam arm 19 to limit the inward movement of the weights 70. The counter balancing weights 70 are maintained in position by nuts 73 threaded on stems 74 and acting through secondary or fractional close balancing plates 75 to clamp the group of weights 70 together against the stops 72.

It is believed that the operation of the pump jack or pump actuating unit provided by the invention will be readily apparent from the foregoing detailed description. The motor 36 normally operates continuously to rotate the sprockets 53 through the gear and chain drive described above. The drive is such that there is a substantial reduction in speed between the motor 25 shaft 38 and the sprockets 53. The rods 60 connecting the rotating sprockets 53 with the stationary base 14 provides for the oscillation of the walking beam 11 during rotation of the sprockets. The provision of the plurality of openings 30 69 in each sprocket 53 for receiving the pins 68 allows for the changing in the length of the stroke of the walking beam 11. The openings 69 are spaced different distances from the axis of rotation of the sprockets 53 and the arrangement of 35 the pins 68 in the different openings 69 changes the stroke of the walking beam 11. The unit is particularly simple and compact in construction as all of its parts are directly associated with the "Samson" post and walking beam. The power 40 means 12 is adjustably supported on the "Samson" post 10 in a simple effective manner, while the drive 13 for operating the walking beam 11 is associated with the pivotal mounting of the beam and with the outer arm 19 of the beam. 45

The sprockets 53, in being carried on the outer arm 19 of the walking beam operate to aid in counter-balancing the string of pump rods R. In practice, the sprockets 53 may be comparatively heavy and thus reduce the number of counter- 50 balancing weights necessary on the outer arm of the walking beam. The pump actuating mechanism may be readily installed as a unit and occupies a minimum amount of space at the well. The mechanism is efficient and inexpensive of 55 operation, and operates smoothly and effectively.

Having described only a typical preferred form and application of my invention, I do not wish to restrict myself to the specific form and application set forth, but wish to reserve to myself any 60 changes or variations that may appear to those skilled in the art or fall within the scope of the following claims.

Having described my invention, I claim:

1. A pump actuating mechanism including, a walking beam, a post supporting the walking beam, power means on the post, and an operating drive between the power means and the walking beam, the said drive including a sprocket carried by the walking beam at a point spaced from the pivotal axis of the walking beam, and an operative connection between the power means and sprocket.
2. A mechanism of the character described including, a pivotally mounted walking beam, a

- power means, and a drive between the power means and the walking beam including, a sprocket carried by the beam at a point spaced from its pivotal axis, and a driving connection between the power means and sprocket. 5
3. A mechanism of the character described including, a pivotally mounted walking beam, a power means, and a drive between the power means and the walking beam including, a rotatable member on the walking beam at a point spaced from its pivotal axis, and a rod pivotally connected to a relatively fixed object and pivotally connected to the member at a point spaced from its axis of rotation. 10
15. 4. A mechanism of the character described including, a pivotally mounted walking beam, a power means, and a drive between the power means and the walking beam including, a rotatable member operated by the power means and having an axis of rotation substantially coincident with the pivotal axis of the walking beam, a rotatable member mounted on the beam at a point spaced from the pivotal axis of the beam, a drive between the members, and a rod pivotally connected to a relatively fixed object and pivotally connected to the second mentioned member at a point spaced from its axis of rotation. 20
25. 5. A pump actuating mechanism including, a walking beam, means pivotally supporting the walking beam, and means for operating the walking beam, the last mentioned means including a stationarily mounted motor, and a rotating sprocket on the walking beam driven by the motor. 30
35. 6. A pump actuating mechanism including, a post, a walking beam, means pivotally mounting the walking beam on the post, a motor on the post, and a drive between the motor and the walking beam including a shaft associated with the said means and rotated by the motor, a sprocket on the shaft, a larger sprocket mounted on the walking beam a substantial distance from said means, an element operatively connecting the two sprockets, and a rod pivotally connected to a relatively fixed object and pivotally connected to the said larger sprocket at a point offset from its axis of rotation. 40
45. 7. A pump actuating mechanism including, a post, a walking beam, means pivotally mounting the walking beam on the post, a motor on the post, and a drive between the motor and the walking beam including a shaft associated with the said means, a speed reducing drive between the motor and the shaft, a rotatable member on the walking beam at a point removed from said 50
- means, a rod pivotally connected to a relatively fixed object and pivotally connected to the member at a point spaced from its axis of rotation. 5
8. A pump actuating mechanism including, a post, a walking beam, means pivotally mounting the walking beam on the post, a motor on the post, and a drive between the motor and the walking beam including a shaft associated with the said means, a speed reducing drive between the motor and the shaft, a rotatable member on the walking beam at a point removed from said means, a rod pivotally connected to a relatively fixed object and pivotally connected to the member at a point spaced from its axis of rotation, 10
15. and a speed reducing drive between the shaft and member. 15
9. In a pump actuating mechanism of the character described, a walking beam, an arc member for carrying a flexible element to be connected to the part to be actuated, and means for removably attaching the arc member to the walking beam in a manner so that it may be swung out of alignment with the said part to be actuated, said means including spaced removable bolts passing through openings in the member and beam transverse of the longitudinal axis of the beam, one of the bolts being located adjacent the center of gravity of the arc member so that the arc member is substantially statically balanced when pivoted on said bolt. 20
25. 10. A mechanism of the character described including, a pivotally mounted walking beam, a power means, and a drive between the power means and the beam including a rotatable member on the beam at a point spaced from the pivotal axis of the beam, a drive between the power means and the member, and a rod pivotally connected to a relatively fixed object and pivotally connected to the member at a point spaced from its axis of rotation. 30
35. 11. A mechanism of the character described including, a pivotably mounted walking beam, one arm of the beam being adapted to operate a pump part, a power means, and a drive between the power means and the beam including a rotatable member on the other arm of the beam at a point spaced from the pivotal axis of the beam, the member being of substantial weight to form a counter balance for the pump part, and a rod pivotally connected to a relatively fixed object and pivotally connected to the member at a point spaced from its axis of rotation. 40
45. 50

EDGAR W. PATTERSON.
